CATHODE-RAY CIRCUIT

William M. Hall, Lexington, Mass.

Application September 6, 1944, Serial No. 552,923

10 Claims. (Cl. 315—22)

1

The present invention relates broadly to cathode ray oscilloscope circuits, and more particularly to circuits for increasing the intensity of the signal trace on the screen of a cathode-ray tube in response to impulses of extremely short duration.

The screen of a cathode-ray tube consists of a thin layer of luminescent material which, under bombardment by rapidly moving electrons, gives rise both to fluorescence or emission of light during bombardment and to phosphorescence or emission of light after bombardment. Because of build-up characteristics of the screen material, in conventional cathode ray tube circuits, a short signal pulse applied to the control grid of the tube will not instantaneously build up the screen flash to peak amplitude. Where pulses in the order of one microsecond are employed, such as those utilized for pulse-echo object location applications, the duration of the pulse is less than the finite time required before screen flash is attained. Accordingly, the flash intensity of fluorescence will be proportional both to the signal strength and its time of duration.

It is, therefore, an object of the present invention to provide a cathode-ray tube circuit for increasing the intensity of signal trace upon the application of sharply defined impulses.

Another object of the present invention is to provide a circuit of the above type which does not substantially affect the signal-to-noise ratio of the screen trace.

For a better understanding of the invention, together with other and further objects thereof, reference is had to the following description taken in connection with the accompanying drawings, wherein like parts are indicated by like reference numerals. The scope of the invention will be pointed out in the accompanying claims.

In the accompanying drawings:

Figure 1 is a schematic circuit diagram of a preferred embodiment of the present invention.

And Figure 2 is a schematic circuit diagram of another preferred embodiment of the present invention.

Referring now to the drawing and more particularly to Figure 1, an intensity control circuit for a cathode ray tube 10 is provided comprising a diode vacuum tube 11, a capacitor 12, and a resistor 13. The signal pulse 14 is applied to terminals 15 and is of a polarity rendering diode 11 conductive through coupling capacitor 16 and capacitor 12. The resultant charge on capacitor 12 is impressed upon the grid control circuit of cathode ray tube 10, being maintained thereon for a period determined by the time constant of capacitor 12 and shunt resistor 13. Capacitor 12 is unable to discharge through diode 11 and must, therefore, discharge through resistor 13.

During the time of the signal pulse and the dis-

2

charge period of capacitor 12, the signal trace will remain intensified; the leading edge of the signal trace will appear steep while the trailing edge will assume the shape of an exponential decay. By adjusting the time constant of capacitor 12 and resistor 13, the holding voltage may be maintained until screen fluorescence has been reached. In practice, it has been found that this holding period should be from 10 to 100 microseconds duration, in which case capacitor 12 may be small in the order of five micro-micro-farads, and resistor 13 may be large in the order of five meg-ohms.

Another method of increasing the intensity of the screen trace and one which will improve the shape of the trailing edge of the signal present in Figure 1 is disclosed in Figure 2. It will be seen that resistance 13 of Figure 1 has now been supplanted by a triode 17 which functions essentially as a clamping tube. The grid of triode 17 is initially biased beyond cutoff by a voltage obtained from a battery 18. A pulse delay line 19 is provided, one end of which is connected to the plate of diode 11, the other end thereof being connected to the grid of triode 17 through a coupling capacitor 20. The delay line 19 is terminated in its characteristic impedance by a resistor 21. When an impulse is applied to terminals 15, condenser 12 is charged through diode 11 thereby impressing an intensifying voltage on the grid of cathode ray tube 10. When the incoming pulse passes delay line 19 after an interval determined by the length thereof, it applies a voltage to the grid of triode 17 having a magnitude and polarity which overcomes the bias of battery 18 thereby rendering said triode conductive, whereupon condenser 12 proceeds to discharge therethrough. Inasmuch as delay line 19 is terminated in its characteristic impedance, no reflection of the incoming pulse is possible; hence interference with succeeding incoming signals is averted. It will be noted that no steady plate potential is applied to the space-current path of triode 17, the sole exciting potential thereon being the charge on capacitor 12.

It is evident that increasing the length of the delay line 19 will cause an increase of screen intensification. The advantage of incorporating the clamping tube 17 into the circuit is to cut off the trailing edge of the tube trace, thus improving the signal-to-noise ratio.

While there has been described what are at present considered preferred embodiments of the invention, it will be obvious to those skilled in the art that various changes and modifications may be made therein without departing from the invention, and it is, therefore, aimed in the appended claims, to cover all such changes and modifications as fall within the true spirit and scope of the invention.

I claim:

1. Apparatus for increasing the intensity of signal trace on a cathode ray tube screen comprising a capacitor connected in the control grid circuit of the cathode ray tube, a triode vacuum tube having its plate circuit connected across said capacitor, a diode vacuum tube, an artificial transmission line, and means for simultaneously applying an incoming pulse to said condenser through said diode and to the grid of said triode tube through said transmission line whereby a voltage is maintained on the control grid of said cathode ray tube for a period determined by the length of said line.

2. A network for increasing the duration of spaced discrete signals, comprising a pair of input terminals to which said signals are applied, a capacitor connected to said terminals in series with unidirectional conducting means whereby said capacitor is charged by said signals, a normally non-conducting electron tube having its space-current path connected across said capacitor, a circuit connected to said input terminals for rendering said tube conducting in response to said signals, said circuit having delay means therein whereby the charge on said capacitor is retained for a period determined by the delay time of said delay means, and an output circuit for said network connected across said capacitor.

3. A network for increasing the duration of spaced pulses comprising a pair of input terminals to which said pulses are applied, a capacitor connected to said terminals in series with unidirectional conducting means whereby said signals charge said capacitor, an electron tube including at least one control grid and having its space-current path connected across said capacitor, a cutoff potential on said grid for normally blocking said space-current path, and a circuit responsive to said pulses for unblocking said space-current path, said circuit including a delay line connected between said input terminals and said control grid, whereby the charge on said capacitor is maintained for a period determined by the delay produced by said delay line, and an output circuit for said network connected across said capacitor.

4. A network for increasing the duration of spaced pulses comprising a pair of input terminals to which said pulses are applied, a capacitor connected to said terminals in series with unidirectional conducting means for applying said signals to charge said capacitor, an electron tube including at least one control grid and having its space-current path connected across said capacitor and excited solely by the charge on said capacitor, a cutoff potential on said grid for normally blocking said space-current path, and a circuit responsive to said pulses for unblocking said space-current path, said circuit comprising a delay line connected between said input terminals and said control grid, whereby the charge on said capacitor is maintained for a period determined by the delay produced by said delay line, and an output circuit for said network connected across said capacitor.

5. A pulse widening circuit comprising a condenser which may be charged by an incoming pulse, a delay network connected to said condenser to be operative after a predetermined interval, and a radio tube connected to said delay network through which said condenser is discharged after said interval.

6. A pulse widening circuit comprising a condenser charged by an incoming pulse, a delay network connected across said condenser, a radio tube having an anode, grid and cathode with its anode-cathode circuit connected across said condenser and its grid connected to said delay network, whereby a potential is impressed upon said grid to discharge said condenser through said anode-cathode circuit after a predetermined interval.

7. A network for spaced discrete pulses comprising a pair of circuits adapted to be excited in parallel from said source, an asymmetrically conducting element in only one of said circuits, a capacitor connected in series with said element, said element being connected to permit rapid charging of said capacitor by said pulses, a normally open switch for discharging said capacitor, and means in the other of said circuits and responsive to said pulses to provide discrete potentials which are delayed relative to said pulses, and means responsive to each of said potentials to close said switch thereby to discharge said capacitor.

8. A network for spaced discrete pulses comprising a pair of circuits adapted to be excited in parallel from said source, an asymmetrically conducting element in only one of said circuits, a capacitor connected in series with said element, said element being connected to permit charging of said capacitor by said pulses, a space-discharge path of normally high impedance connected across said capacitor, and means in the other of said circuits and responsive to said pulses to provide discrete potentials which are delayed relative to said pulses, and means responsive to each of said potentials to lower the impedance of said space-discharge path conducting thereby to discharge said capacitor.

9. A network for spaced discrete pulses comprising a pair of circuits adapted to be excited in parallel from said source, a conducting diode in only one of said circuits, a capacitor connected in series with said diode, said diode being poled to permit charging of said capacitor by said pulses, a normally non-conducting space-discharge path for discharging said capacitor, and means in the other of said circuits and responsive to said pulses to provide discrete potentials which are delayed relative to said pulses, and means responsive to each of said potentials to render said space-discharge path conducting thereby to discharge said capacitor.

10. A network as set forth in claim 9, wherein said space-discharge path comprises an electron tube having anode and cathode electrodes respectively connected to opposite sides of said capacitor, there being no anode biasing potential connected between said cathode and anode.
